UNITED STATES PATENT OFFICE

163,713

STOCKING

Sol Savitz, Philadelphia, Pa.

Application October 5, 1949, Serial No. 5,307

Term of patent 7 years

(CL. D47—7)

To all whom it may concern:

Be it known that I, Sol Savitz, a citizen of the United States, residing at Philadelphia in the county of Philadelphia, and State of Pennsylvania, have invented a certain new, original, and ornamental Design for a Stocking, of which the following is a specification, reference being had to the accompanying drawing forming part thereof:

In the drawing:

Fig. 1 is a side view of a stocking, showing my new design.

Fig. 2 is a rear view of the stocking shown in Fig. 1.

Fig. 3 is a detailed fragmentary view of the rear of the stocking showing my design.

I claim:

The ornamental design for a stocking, substantially as shown.

SOL SAVITZ.
